Patented Feb. 4, 1964

197,439

GASOLINE PUMP OR SIMILAR ARTICLE

Joseph A. Winger, Myron R. Cothorn, and Murry J. Gammill, Greenwich, Conn., assignors to Texaco Inc., New York, N.Y., a corporation of Delaware

Filed Feb. 13, 1962, Ser. No. 68,797

Term of patent 14 years

(Cl. D52—2)

FIGURE 1 is a front perspective view of a gasoline pump showing our new design;

FIGURE 2 is a front elevation thereof;

FIGURE 3 is a right hand side elevation thereof; and

FIGURE 4 is a top plan view thereof.

The undisclosed side of the gasoline pump is substantially the same in appearance as the side shown.

We claim:

The ornamental design for a gasoline pump or similar article, as shown and described.
